[57] CLAIM

The ornamental design for a publicly accessible video teleconferencing kiosk, as shown and described.

DESCRIPTION

FIG. 1 is a front orthographic projection of the ornamental design for a publicly accessible video teleconferencing kiosk in a first embodiment;

FIG. 2 is a rear orthographic projection of the kiosk in a first embodiment;

FIG. 3 is a left orthographic projection of the kiosk in a first embodiment;

FIG. 4 is a right orthographic projection of the kiosk in a first embodiment;

FIG. 5 is a top orthographic projection of the kiosk in a first embodiment;

FIG. 6 is a bottom orthographic projection of the kiosk in a first embodiment;

FIG. 7 is a front orthographic projection of the ornamental design for a publicly accessible video teleconferencing kiosk in a second embodiment which differs from the first embodiment in the addition of a planter at the base thereof;

FIG. 8 is a rear orthographic projection of the kiosk in a second embodiment which differs from the first embodiment in the addition of a planter at the base thereof;

FIG. 9 is a left orthographic projection of the kiosk in a second embodiment which differs from the first embodiment in the addition of a planter at the base thereof;

FIG. 10 is a right orthographic projection of the kiosk in a second embodiment which differs from the first embodiment in the addition of a planter at the base thereof;

FIG. 11 is a top orthographic projection of the kiosk in a second embodiment which differs from the first embodiment in the addition of a planter at the base thereof; and,

FIG. 12 is a bottom orthographic projection of the kiosk in a second embodiment which differs from the first embodiment in the addition of a planter at the base thereof;
